UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

DOUBLE-CUSHION TRUNK.

Application filed September 9, 1927. Serial No. 218,478.

This invention relates to improvements in double cushion trunks.

Wardrobe trunks are usually divided vertically into two parts to form a wardrobe 5 section and a drawer section. The two sections are hinged together to swing horizontally to open or closed position, and one of the sections is formed with an upper open 10 end closed by a top cover. The wardrobe section is provided with garment hangers for suspending outer wearing apparel thereon, and the other section is provided with drawers for holding other articles of wear.

It is one of the objects of the present invention to provide a wardrobe trunk of the before mentioned type, having inner top and front covers in which both the inner and the outer top covers are provided with inner cushions to properly maintain the 20 garments, mounted on the hangers, in position.

A further object of the invention is to provide a double cushion trunk in which one cushion will reinforce the other in maintaining the garments in position on the hangers.

A further object of the invention is to provide a double cushion trunk which is of simple construction, is strong and durable and is well adapted for the purpose described.

With the above and other objects in view, the invention consists of the improved double cushion trunk and its parts and combinations as set forth in the claims, and all 35 equivalents thereof.

In the accompanying drawings, in which the same reference numerals indicate the same parts in all of the views:

Fig. 1 is a front view of the improved 40 trunk provided with the double cushions, the trunk being shown in open position; and

Fig. 2 is a front view of the trunk shown in closed position, parts broken away to show interior construction.

Referring to the drawings, the numeral 45 5 indicates the wardrobe section, and 6 the drawer section, of a wardrobe trunk, which are hinged together to swing horizontally to open or closed position. The wardrobe section is formed with an open front 7 closed by an inner hinged door 8, and is also formed with an open top 9 closed by an inner top cover 10. The drawer section 6 is also provided with an outer top cover 55 11 which is adapted to swing over the open

end of the wardrobe section and the inner top cover 10 when the two sections are in closed position, as shown in Fig. 2.

The wardrobe section adjacent its upper open end, and on opposite inner sides, is 60 provided with parallel tracks 12 upon which are slidably and removably mounted garment hangers 13. The hangers are formed with upper straight edge portions 13' over which garments are draped and supported. 65 In order to hold the draped garments in position, and to prevent abrasion of the garments, the top cover 10 is provided with a cushion or pad 14, into which the upper edge portions of the hangers or garments 70 draped thereon imbed when the inner top cover is in closed position. The pad 14 is secured to the underside of the inner top cover and is of a thickness greater than the distance between the upper edge portions of 75 the garment hangers and the lower surface of the inner top cover to securely hold the hangers and the garments thereon in place. The inner top cover 10 is hinged to the upper edge portion of the inner door 8 and 80 swings into position over the garment hangers 13 and may be locked in said position in any manner desired. The top cover is formed of light thin material, and to reinforce the same, the outer cover 11 on its inner side is provided with a cushion or pad 15 which is of a thickness greater than the 85 distance between the upper surface of the inner cover and the inner surface of the outer cover to exert a yielding pressure on 90 said inner cover, and thus reinforce the said inner cover 10 against outward strain. The outer top cover 11 is locked in closed position 95 by a lock 16.

When in closed position, the garments draped over the upper edge portions of the hangers will be held in position without wrinkling and against accidental displacement. Furthermore, the pad will also hold the garment hangers in position, so that garments draped on lower portions of the hangers will be maintained in position.

From the foregoing description, it will be seen that the double cushion trunk is of very simple construction, and is well adapted 105 for the purpose described.

What I claim as my invention is:

1. A double cushion trunk, comprising a trunk formed of two hinged together sections movable horizontally to open position, 110

one of said sections having an open top and an open front closed by the other section, an outer top cover for the open top, a track mounted in the section with the open top, 5 garment hangers mounted on said track, an inner top cover for the open top having a cushion mounted on its lower side into which the garment hangers or garments draped thereon imbed, and a cushion connected to 10 the lower side of the outer top cover which engages the inner top cover when the parts are in closed position.

2. A double cushion trunk, comprising a trunk formed of two hinged together sections movable to open position, one of said sections having an open top and an open front closed by the other section, an outer top cover for the open top, tracks mounted in the section with the open top, garment 20 hangers slidably mounted on the tracks, a hinged inner top cover for the open top having a cushion mounted on its lower side into which the garment hangers or garments draped thereon imbed, and a cushion 25 mounted on the lower side of the outer top cover which yieldingly engages and reinforces the inner top cover when the parts are in closed position.

3. A double cushion trunk, comprising a trunk formed of two hinged together sections movable to open position, one of said sections having an open top and an open front closed by the other section, an outer top cover for the open top, an inner door 35 for the open side, tracks mounted within the upper portion of the section with the open top, garment hangers slidably mounted on the tracks, an inner top cover for the

open top hinged to the upper edge of the inner door, a cushion mounted on the lower side of the inner top cover into which the hangers or the garments draped thereon imbed, and a cushion mounted on the lower side of the outer top cover which yieldingly engages and reinforces the inner top cover 40 when the parts are in closed position.

4. A double cushion trunk, comprising a trunk formed of a wardrobe section and a drawer section hinged together and swingable horizontally to open position, the wardrobe section having an open top and an open front closed by the drawer section, an outer top cover hinged to the forward edge of the drawer section for closing the upper open end of the wardrobe section, tracks within 55 the upper portion of the wardrobe section, garment hangers slidably mounted on the tracks and having horizontally extending upper edge portions, an inner front door interposed between the two sections and hinged to the wardrobe section for closing the open front of said section, an inner top cover hinged to the upper edge portion of the inner front door for closing the top opening 60 of the wardrobe section, a cushion covering the major portion of the lower side of the inner top cover and into which the garment hangers or the garments draped on the horizontal edge portions thereof imbed, and a cushion mounted on the lower side of the outer top cover which yieldingly and reinforcingly engages the inner top cover when 65 both covers are in closed position.

In testimony whereof, I affix my signature.

JULIUS RITTER, JR.
